ASSIGNOR TO SAID LATHROP.

CAN-REVERSING MECHANISM FOR CAN-WASHING MACHINES.

1,336,567.

Specification of Letters Patent.

Patented Apr. 13, 1920.

Original application filed February 16, 1917, Serial No. 149,102. Divided and this application filed July 19, 1917. Serial No. 181,565.

To all whom it may concern:

Be it known that we, HARRY D. LATHROP and WALTER H. PAULSON, citizens of the United States, and residents of the city of Chicago, county of Cook, and State of Illinois, have invented certain new and useful Improvements in Can-Reversing Mechanism for Can-Washing Machines, of which the following is a specification.

10 Our invention relates to improvements in can reversing mechanism for can washing machines, the present application being a division of our pending application, Serial No. 149,102, filed February 16, 1917, for improvements in can washing machines.

15 The object of this invention is the production of reversing mechanism designed for use in connection with milk can washing machines, which will be rapid and positive in 20 operation, one which will permit of manual operation at a minimum exertion on the part of the operator, and one which will be of durable and economical construction.

Other objects will appear hereinafter.

25 The invention consists in the combinations and arrangements of parts hereinafter described and claimed.

30 The invention will be best understood by reference to the accompanying drawings, forming a part of this specification, and in which,

35 Figure 1 is a side elevation of a milk can washing machine equipped with can reversing mechanism embodying the invention,

40 Fig. 2, a slightly enlarged vertical longitudinal section of the discharge end of the machine, and

Fig. 3, a detail section taken on line 3—3 of Fig. 2.

45 The preferred form of construction as illustrated in the drawings, comprises a suitable framework 10 in which are provided superposed horizontally extending guides 11 and 12 for the cans and covers to be cleaned.

50 Suitable mechanism is provided, operable by an oscillatory manually operable lever 13, fulcrumed at 14, for effecting intermittent feeding or advancing of the cans and covers through the machine, on the guides 11 and 12. In this intermittent feeding or advancing of the cans and covers through the machine, the same are subjected to a cleansing, sterilizing and drying process, the mechanism for effecting such treatment of the cans

and covers and for advancing or feeding the same through the machine, not being claimed in this application, and hence detail description thereof is omitted.

After the cans and covers have passed through the cleansing process, as mentioned, the same are ready for discharge from the machine and to this end are passed from the guides 11 and 12 on to inclined guides 15 and 16, respectively, down which said cans and covers are adapted to slide by gravity. The cans which are designated by the letter "A," in the passage of the same along the guide 11, are in an inverted position, and as each can is discharged or pushed from the guide 11, the same drops to position in a substantially semi-cylindrically formed can reversing member 17 which is arranged at the discharge end of said guide, said member 17 being pivotally mounted at 18 for pivotal movement about a transverse axis which is located substantially midway between the ends of said member, as clearly seen in Fig. 2.

The member 17 is of a size to snugly receive the can, end pieces 19 and 20 being adapted to engage with the opposite ends of the can to hold the same against relative longitudinal movement. The normal position of the can reversing member 17, as seen in Fig. 1, is one in which the same is adapted to receive a can discharged from the guide 11. Actuation of said member 17 to effect reversal of the can is effected by means of a toggle 21 fulcrumed at 22, the opposite end of said toggle being connected at 23 with one end of said member 17. Actuation of said toggle is effected by means of a link 24 which is pivotally connected at one end with the lower end of an oscillatory arm 25 fulcrumed intermediate its ends as at 26. The upper end of arm 25 is arranged in the path of a roller 27 carried by a reciprocating rod 28 having operative connection with the actuating lever 13, the arrangement being such that, upon oscillation of said lever 13, rod 28 will be reciprocated to carry the roller 27 into engagement with the upper end of arm 25, causing oscillation of the same to the left as seen in the several figures of the drawings. When this occurs the lower link 105 of toggle 21 will of course be rocked to the left causing breaking to the left of the toggle with the result of causing oscillation of

the can reversing member 17 to a position shown in Fig. 2. When said member 17 reaches this position, the can drops by gravity therefrom on to the inclined guide 15 down which the same moves by gravity.

5 The upper end of the arm 25 is offset as at 25' in order to form a shoulder which will 10 assume horizontal position when the can reversing member 17 is in reversing position as seen in Fig. 2. The movement of the 15 roller 27 is such that, as the can reversing member reaches reversing position, said roller will travel on to the horizontal shoulder or portion 25' of the arm 25, as clearly 20 seen in Fig. 2, and thus serve to positively lock said arm and hence the can reversing member in can reversing position. Said can reversing member will not be permitted to return to initial or can receiving 25 position until the bar 28 carrying the roller 27 is moved rearwardly through manual tilting of the lever 13. When this is done, the reversing member will rock by gravity back to its initial position to receive another can.

25 Each subsequent can is similarly handled. In order to lock the reversing member 17 in can receiving position so as to adapt the same to withstand the rough usage to which the same is subjected by reason of the 30 dropping of a can to position thereon, the arrangement and operation of the toggle 21 is such that the same passes beyond dead-center position in the return rocking of the reversing member 17. This movement of 35 the toggle to a position beyond the dead-center is insured by a weight 24' provided upon one end of the link 24, as clearly seen in Fig. 2. With this arrangement it will be seen that the pressure or weight of the can 40 upon the reversing member, cannot possibly effect swinging of the reversing member to can reversing position, such swinging of said reversing member being effected only upon breaking of the knee joint of the toggle which is effected through manual tilting of the lever 13 as before described. After breaking of the knee joint, continued 45 oscillation of the lever 13 causes the oscillatory movement of the reversing member to effect reversal of the can. It will thus be seen that the can reversing member is at all 50 times under the control of the manually operable lever 13, actuation thereof to or from reversing position being effected only 55 through manual actuation of said lever.

By locating the axis of the reversing member intermediate the ends thereof, the space

necessary for the operation of the same, is reduced to a minimum, it being clear that with the axis located at either end of the reversing member, a considerably greater space would be required to allow for the swinging of the member. Also with this arrangement, the parts are so balanced that actuation of the can reversing member may 60 be effected through minimum exertion on the part of the operator, on the control lever 13.

While we have illustrated and described the preferred form of construction for carrying our invention into effect, this is capable of variation and modification without departing from the spirit of the invention. We, therefore, do not wish to be limited to the precise details of construction set forth, 70 but desire to avail ourselves of such variations and modifications as come within the scope of the appended claims.

Having described our invention what we claim as new and desire to secure by Letters 80 Patent is:

1. In a can washing machine, can reversing mechanism comprising an oscillatory element adapted to receive and reverse a can deposited thereon; means for effecting actuation of said reversing element, said means comprising an oscillatory arm; a reciprocating member adapted to engage with and rock said arm in actuating said reversing element; and a shoulder on said arm adapted for engagement by said reciprocating member, when said element is in can reversing position, to lock the same in this position, substantially as described.

2. In a can washing machine, can reversing mechanism comprising an oscillatory element adapted, in the receiving position thereof, to receive a can deposited thereon; means for oscillating said element to reverse the can, said last mentioned means comprising a toggle; a stop whereby said toggle is locked past dead-center when said reversing member is in receiving position; and means for actuating said toggle, substantially as described.

105 In testimony whereof we have signed our names to this specification in the presence of two subscribing witnesses.

HARRY D. LATHROP.
WALTER H. PAULSON.
